UNITED STATES PATENT OFFICE

JAMES H. CLARK, OF DETROIT, MICHIGAN, ASSIGNOR TO BRIGGS MANUFACTURING COMPANY, OF DETROIT, MICHIGAN, A CORPORATION OF MICHIGAN

REMOTE-CONTROL-LEVER ASSEMBLY FOR DOOR LATCHES

Application filed January 3, 1927. Serial No. 158,752.

This invention relates generally to remote control lever assemblies for door latches such as that shown and described in co-pending application Serial No. 123,535 and consists of certain novel features of construction, combinations and arrangements of parts as will be hereinafter more fully described and particularly pointed out in the appended claims.

In the accompanying drawings:

Figure 1 is an outside elevation of an assembly embodying my invention.

Figure 2 is a vertical sectional view taken on the line 2—2 of Figure 1.

Figure 3 is an inside elevation of the construction shown in Figure 1.

Figure 4 is an outside elevation of a slightly modified form of construction.

Figure 5 is a vertical sectional view taken on the line 5—5 of Figure 4.

Referring now to the drawings; 1 is a lock board constituting an inner panel of a door, and 2 is a lever of an assembly embodying my invention. As shown, this lock board 1 is provided with an arcuate-shaped slot 3 and is provided along the lower curved edge and at the ends of said slot with inturned flanges 4 and 5 respectively. Preferably the flange 4 at the lower edge of the slot curves upwardly in spaced relation to

the inner face of the lock board and serves as a shield for the lever 2 and a stiffening and reinforcing member for the lock board. The flanges 5 at the ends of the slot preferably project at substantially right angles to

the lock board and serve as abutments or stops for the lever. As shown this lever 2 has a substantially flat attaching portion 6 and an offset longitudinally curved portion 7. Preferably the attaching portion is dis-

posed upon the inner side of and is pivotally connected to the lock board 1 at a point above and concentric with the arcuate slot 3, while the curved portion 7 is spaced from and is movable freely over the outer side of the lock board. In the present instance the upper end of the attaching portion 6 is offset slightly inwardly and is secured to a suitable actuating link 8 for the latch bolt at one edge of the door, while the lower end of the at-

taching portion 6 is offset slightly inwardly

and connects into the inner end of the curved portion 7. Preferably this curved portion 7 extends through the arcuate slot 3 and is provided at its lower end with an outwardly projecting lateral portion 9 to which a suitable operating handle 10 is preferably secured.

To provide a neat appearance a panel 11 of fabric trimming material is secured upon the outer face of the lock board and has an arcuate slot 12 therein registering with the slot 3, while mounted upon the outer face of this trimming material is an escutcheon 13 that is also provided with an arcuate slot 14 in registration with the slots 12 and 3. Preferably this escutcheon 13 is secured at its ends to the lock board 1 by means of screws 15 and is provided along the edges of the slot 14 with inturned flanges 16 that overlap and thereby conceal the edges of the slot 12 in the panel 11 of trimming material.

In Figures 4 and 5 I have shown a slight modification in which the lever 20 has a substantially flat attaching portion 21 and a longitudinally curved portion 22. Preferably the attaching portion 21 is disposed upon the inner side of and is pivotally connected to the lock board 1 at a point below and concentric with the arcuate slot 23, while the curved portion 22 constitutes a handle for the lever and is movable freely over the outer side of the lock board. With this construction the attaching portion 21 is connected at its lower end to the actuating link 8 for the latch bolt and is provided at its upper end with an inwardly offset portion 24, while the curved portion 22 extends through the slot 23 and connects into the upper end of the offset portion 24.

Thus, from the foregoing description, it will be readily apparent that the levers shown and described may be readily operated about their respective pivots to actuate the bolt and other mechanism such as a suitable dog of the latch. It will also be apparent that such lever assemblies can be manufactured at a very low cost, are strong and durable, are neat in appearance, and can be readily and separately installed.

While it is believed that from the forego-

ing description, the nature and advantage of my invention will be readily apparent, I desire to have it understood that I do not limit myself to what is herein shown and described and that such changes may be resorted to when desired as fall within the scope of what is claimed.

What I claim as my invention is:

1. In an assembly of the class described, the combination with a panel having an arcuate slot therein, of a lever having an intermediate transversely extending portion extending through the slot and having oppositely extending longitudinal portions disposed upon opposite sides of said panel, one of said longitudinal portions being bowed outwardly with respect to said panel and spaced therefrom, and the other of said longitudinal portions being pivotally connected to said panel and having means for receiving a remote control link attaching means.

2. In an assembly of the class described, the combination with a panel having an arcuate slot therein, of a lever having a portion extending through the slot and having other portions upon opposite sides of said panel, one of said last mentioned portions being substantially flat and being connected directly to the panel, the other of said last mentioned portions being bowed outwardly with respect to said panel and spaced therefrom.

3. In combination, a lever having an attaching portion and a longitudinally curved portion, and a support for said lever having a slot receiving a portion of said lever and having flanges at certain edges of said slot constituting a shield and stops for said lever.

4. In combination, a lever having an attaching portion, and a longitudinally curved portion offset with respect to said attaching portion, and a support for said lever having a slot receiving a portion of said lever, a pivot for the lever carried by the support and engaging said attaching portion intermediate the ends thereof, said attaching portion being provided at its free end beyond the pivot with means for receiving a remote control link attaching means, a panel of trimming material upon the outer side of said support and having an arcuate slot registering with the slot aforesaid, and an escutcheon on the outer side of said panel of trimming material having an arcuate slot registering with the slot aforesaid and having inturned flanges at the edges of said slot overlapping and concealing the edges of the slot in said panel of trimming material.

5. In combination, a lever having an attaching portion and a portion offset with respect to said attaching portion, a support for said lever having a slot receiving a portion of the lever, the attaching portion of said lever being pivotally connected to the support and having a portion provided with means for receiving a remote control link at-

taching means, a panel of trimming material upon the outer side of said support and having a slot registering with the slot aforesaid, and an escutcheon on the outer side of said panel of trimming material having a slot registering with the slot aforesaid and having inturned portions at the edges of said slot overlapping and concealing the edges of the slot in said panel of trimming material.

6. In combination, a lever having an attaching portion and a portion offset with respect to said attaching portion and an intermediate connecting portion, a support for said lever disposed between said attaching and offset portions and having a slot receiving the intermediate connecting portion of the lever, the attaching portion of said lever being pivotally connected to the support and provided with means for receiving a remote control link attaching means, a panel of trimming material upon one side of said support between said support and the offset portion of said lever and having a slot registering with the slot aforesaid and receiving the connecting portion of said lever, and an escutcheon on one side of said panel of trimming material between said panel and the offset portion of said lever and having a slot registering with the slot aforesaid and receiving the connecting portion of said lever, and flanges at the edges of the slot in said escutcheon extending into the slot in said panel of trimming material and overlapping and concealing the edges of the slot in said panel of trimming material.

In testimony whereof I affix my signature.

JAMES H. CLARK.
